MAUDE MAYO BENTZ, OF MONTCLAIR, NEW JERSEY

HUMIDIFIER AND DEFLECTOR DEVICE

Application filed April 26, 1928. Serial No. 273,077.

My invention relates to a combined humidifier and deflector device particularly adapted for use in connection with heat radiators of steam, hot water and like heating systems. An object of the present invention is to provide a simple and efficient device adapted for use as an auxiliary to the usual radiator for deflecting the air current outwardly into the room and to add to the deflected air current a desirable percentage of moisture so as to render the atmospheric conditions in the room more conducive to comfort and health and better calculated to keep the furniture and woodwork within the dwelling in good condition.

Particularly valuable features of the present improvements consist of an improved construction allowing of better circulation of the deflected air current resulting in materially higher efficiency than has been accomplished by structures as heretofore proposed; and further in the improved form, arrangement and spacing of the wicks employed which are of an improved form and arrangement adapted to facilitate removal for cleaning and replacement and which in addition are particularly effective while offering the minimum of resistance to the air circulation.

The aforesaid and other features and advantages of my improved construction will be more fully understood by reference to the accompanying drawings, wherein like reference characters are applied to the corresponding parts in the several views.

In the drawings,—

Fig. 1 is a perspective view of my improved device shown in place upon a heating radiator.

Fig. 2 is a vertical transverse sectional view thereof taken on line 2—2 of Fig. 3.

Fig. 3 is a vertical longitudinal sectional view taken on line 3—3 of Fig. 2.

Fig. 4 is a detail perspective view of a wick element.

Fig. 5 partial detail sectional view of the wick construction.

Fig. 6 is a fragmentary perspective view of the wick supporting bar structure.

Fig. 7 is a perspective view showing a de-

sirable modified construction employing a sliding type of cover.

Referring to the drawing wherein there is shown an approved embodiment of my invention, the humidifier and deflector device comprises a suitable water receptacle or trough 1 of a size and form to allow of it being placed upon a heating radiator as shown in Fig. 1. The end wall members 2—2 of the trough are enlarged vertically and rearwardly to form a support for a deflecting cover or shield suitably spaced from the radiator and trough to provide an upwardly and forwardly extending passage for deflecting outwardly the rising heated air column at the rear of the radiator. The deflector cover, as shown, is composed of the rigidly supported rear deflecting plate 3 connected at its ends to the end wall members 2 and the hinged cover plate 4 pivotally supported at its rear edge upon a bearing rod 5 supported by the end wall members 2. The deflecting plate 3 may as shown be extended downwardly to intercept the rising heated air column and is rounded or curved forwardly at its upper portion to direct the air column forwardly over the water trough, as indicated by the arrows, and outwardly through the discharge opening between the forward edge of the trough and the cover plate 4. This discharge opening, as shown, is provided with a wire fabric screen for presenting an improved appearance while allowing for substantially free circulation of the air therethrough. The wire fabric is shown secured at its upper portion to a supporting rod 6 carried by the end walls of the trough and is welded at its lower edge to the inner surface of the front wall of the trough.

A particularly valuable feature of the present improvements consists in a special means for humidifying the air current passing over the water trough. This comprises an advantageous arrangement of moisture absorbing wicks supported to depend within the water supply and reservoir and to present an enlarged area of moistened surface while offering a minimum of resistance to circulation of the air. In accordance therewith, I have provided a series of wick elements 7 of a relative-

ly stiff cotton fabric having metallic stiffener and supporting bars 8 secured to the respective ends of the fabric. For properly positioning the wicks, notched supporting bars or 5 rods 9 are provided and arranged extending longitudinally and immediately beneath the cover plate and carried by the end walls of the trough. The notched bars 9 are formed as shown with spaced notches 10 adapted to receive the projecting bearing portions of the 10 supporting bars 8 of the wicks. The arrangement accordingly provides for equidistantly spacing the exposed portions of the wicks which are likewise supported with the fabric 15 thereof transverse of the trough and parallel to the path of movement of the air current.

As will be appreciated, the wick elements in the desirable arrangement as shown and composed of a relatively stiff fabric are 20 adapted for assuming and maintaining their proper position so as to offer negligible resistance to the free circulation of the air and further contributes materially to the utility of the device by reason of the facility with 25 which the wicks may be removed and replaced for the purpose of cleaning. In the latter connection, it will be further noted that the cover upon being lifted will fully expose the wicks for ready removal.

While I have described and shown a desirable embodiment of the features of my invention, it will be understood that modifications may be made therein without departing from the scope of the invention as defined in 35 the appended claims. As illustrative thereof, I have shown in Fig. 7 a modified structure having the end walls of the trough formed at their upper edges with inturned flanges 10' forming slideways to receive a 40 sliding cover plate 11 in place of the hinged cover plate of the first disclosure.

As shown best in Figs. 4 and 5, the improved wick elements may be inexpensively formed with the supporting and stiffening bars 8 of sheet metal bent upon itself to 45 enclose the marginal end portions of the fabric and secured by spot pressing of the metal as indicated.

The improved structure is particularly 50 adapted for its intended purpose, is highly efficient as a humidifier by reason of large areas of exposed wick surfaces arranged to offer the minimum of resistance to the desired circulation. It further deflects the heated air 55 current outwardly within the room which in conjunction with the cleaning of the air eliminates the soiling of the walls or woodwork common to the usual radiator use.

Having described my invention, I claim: 60

1. A humidifier and deflector device for use with heat radiators comprising a trough member adapted to be positioned upon a radiator, a deflecting shield member supported thereon in spaced relation to the trough to 65 provide an air passage from the rear of the

radiator extending forwardly over the trough member, supporting bars carried by the end wall members of the trough and provided with spaced notches, a plurality of wick elements of fabric and supporting bars attached to the respective ends of the wick elements and adapted for supporting engagement with the notches for supporting the wick elements with depending loops within the trough. 75

2. Air moistening means for a device of the character described comprising a trough member, supporting bars positioned above the trough member and extending longitudinally thereof and formed with oppositely positioned equidistantly spaced notches, a plurality of independently supported wick elements consisting of a relatively stiff fabric and supporting bars attached to the respective ends of the wick elements and adapted for supporting engagement with the notches for supporting said wick elements with depending loops within the trough. 80

3. Air moistening means for a device of the character described comprising a trough member, supporting bars positioned above the trough member and extending longitudinally thereof and formed with oppositely positioned spaced notches, a plurality of independently supported wick elements consisting of a fabric and supporting bars attached to the respective ends of the wick elements and adapted for supporting engagement with the notches to support the wicks with depending loops within the trough, said stiffener bars being formed of sheet metal bent upon itself to enclose the fabric and being spot pressed into securing engagement therewith. 85

Signed at Montclair in the county of Essex and State of New Jersey this 9th day of April A. D. 1928. 105
